UNITED STATES PATENT OFFICE.

MORRIS SHERAS, OF CHICAGO, ILLINOIS, ASSIGNOR TO A. D. JOSLIN MANUFACTURING COMPANY, OF CHICAGO, ILLINOIS, A CORPORATION OF ILLINOIS.

DATING STAMP.

Application filed March 11, 1921. Serial No. 451,512.

To all whom it may concern:

Be it known that I, MORRIS SHERAS, a citizen of the United States, residing at Chicago, in the county of Cook and State 5 of Illinois, have invented certain new and useful Improvements in Dating Stamps, of which the following is a specification.

This invention relates to printing, and pertains particularly to improvements in the 10 structure and organization of hand operated stamps designed primarily as dating stamps.

The general purpose of the invention is the provision of a dating stamp of hand-operated self-inking type, which is adapted 15 to make its printing impression face upwardly, so that the sheet upon which the impression is to be made may be positioned accurately on a platen to insure the impression being made at the proper place, and so 20 that the same may be seen by the operator while the sheet is still on the platen. Various particular objects which are corollary to this general object include the provision of a type setting or date changing mechanism 25 which may be embodied in a very compact form, so that the movable parts of the stamp frame need not be enlarged to an extent rendering them inconvenient or awkward; provision of a type setting structure where- 30 in the type in printing position are securely retained against overthrow, and maintained in proper alignment; the provision of a printing type mechanism including shiftable type wheels, wherein the parts of the 35 mechanism employed for setting or shifting the wheels are completely relieved or protected from all violent pressures or stresses incident to the impact of the stamp in the printing operation, whereby their utility 40 and accuracy for a prolonged period is assured.

A further object is the provision of an improved form of ribbon feed mechanism which may be embodied in small compass, 45 in order that it may be conveniently mounted on the movable head of the stamp, and to make provision in such ribbon feed mechanism for the feeding of the ribbon in either direction incident to the operation of the stamp. This is of importance in that it permits reuse of the ribbon in the stamp 50 without rewinding, thereby greatly extending the term of utility of the ribbon, and eliminating a messy and time-consuming operation.

Other and further objects of the invention will be pointed out hereinafter, indicated in the appended claims, or will be obvious to one skilled in the art upon an understanding of the invention through the 60 following disclosure.

Described generally, the present invention contemplates the provision of a plurality of type wheels which are mounted in a swinging head above a stationary platen; said 65 wheels being of substantial construction and carried on a substantial shaft mounting which will be effective to retain them in alignment under the hard usage to which a stamp of this character is subjected. With these adjustable type wheels is associated a die plate bearing printing characters, and arranged for automatic feed over the faces of both is an inked ribbon, also carried in the movable head, and arranged to be fed step by 70 step in either direction by the ribbon feed mechanism operated incident to the movement of the swinging head. The setting of the date wheels is accomplished by means of a manually operable mechanism which is 75 designed to effect the progressive step by step movement of the wheels selectively. This particularly adapts the stamp for use 80 in banking houses and the like where the dating is for the current day only; the proper type setting being made for each day and the stamp not being employed for the purpose of back dating; and one of the advantages of the present construction is that 85 it prevents confusion or mistake in the setting of the date printing type, by preventing the reverse operation thereof, yet facilitates the proper date setting from day to day. The disposal of the printing and inking members in the movable head or upper 90 pressure member of the stamp, is particularly desirable and advantageous, in that it 95 permits the printing of the impression right side up and in view of the operator, so that the printing may be placed accurately on 100 the sheet which is positioned on the platen. This makes for elimination of movements and operations in the use of the device, as it is not necessary for the operator to remove the printed sheet and turn it over to 105 verify the printing.

The invention will be understood more in detail by reference to the accompanying drawings forming a part of this specification in which one embodiment of the in- 110

vention is disclosed for the purpose of illustration; and while the present disclosure is predicated upon this particular structure, it is to be understood that the same does not 5 constitute the only embodiment of the invention contemplated, and that it therefore is not to be construed as limiting the invention as hereinafter claimed, short of its true scope and standing in the art.

10 In the accompanying drawings—

Fig. 1 is a side elevation of a stamp structure embodying my invention, showing certain internal working parts in dotted lines;

15 Fig. 2 is a part elevation of the opposite side of the stamp showing other internal parts in dotted lines;

Fig. 3 is a top view with casing portions broken away to show internal working parts;

20 Fig. 4 is a detail in the nature of an elevational section taken substantially on line 4—4 of Fig. 3;

Fig. 5 is a detail of the ribbon feed actuating mechanism;

25 Fig. 6 is a detail in the nature of a longitudinal sectional elevation taken substantially on line 6—6 of Fig. 3;

Fig. 7 is an enlarged sectional detail of the date wheel operating mechanism;

30 Fig. 8 is a detail in the nature of a side elevation of the control cam adjusting mechanism;

Fig. 9 is a detail of the control cam shaft; and

35 Fig. 10 is an end view of the same.

Referring to these drawings by means of the reference characters applied, it will be understood that the device includes two principal frame members, viz, a base frame member 1 shaped to provide an effective and substantial support, and a swinging frame member 2 which is pivotally mounted on brackets 4 of the base frame member for vertical oscillatory movement, the extent of movement of the swinging frame member being limited by stops 5 and 6. The base frame member is formed with a recess 7 providing a housing for a spring 8 which bears against the stop 6 and tends to maintain the front end of the swinging frame in its lifted position. The base frame also has a portion forming a bed 9 in which a platen 10 is removably secured by means of a screw 11 seated against a rubber gasket 12. The swinging frame member is shaped at its forward end to form a housing 14 the sides of which are closed by side cover plates 15, upon which is supported a type die member 16; the same being removably mounted by means of screws 17. The printing face of this die member is adapted to impact the surface of the platen 10 when the swinging frame member is depressed, but normally is held lifted from the same by the influence of spring 8. A boss 18 on top of the hous-

ing 14 forms a handle whereby the frame may be depressed. The housing includes inwardly projecting lugs 19, best illustrated in Fig. 6, against which the type die plate 16 bears, and which constitute supporting members for parts of the operating mechanism.

The date wheel mechanism.

The date wheel mechanism includes a transverse shaft 20 fixedly supported in said cover plates 15, and forming a mounting for pawl frame members 21, rotatably mounted thereon, and which are connected by a top frame member 22. The type wheels include a month type wheel 24, day type wheels 25 and 26, and a year type wheel 27. These type wheels are independently rotatable on shaft 20, and each has conjoined to it a ratchet wheel, that of the month type wheel being designated 24', that of the first day type wheel 25', that of the second day type wheel 26' and that of the year type wheel 27'. The month type wheel carries twelve peripheral bosses bearing type characters designative of the months; the first day type wheel carries three series of the characters 1, 2 and 3, the series being interspaced by blanks; the second day wheel carries a series of type characters comprising the numerals 1 to 9 inclusive and "0," while the year type wheel carries type characters indicative of the years. The position of the shaft 20, and the radius of the several type wheels, are such that these type characters may be brought into register with slots in the type die 16, so that in their lowermost positions incident to rotation of the type wheels, their faces will occupy the same plane as the faces of the printing type on the type die, and so that they may cooperate with the platen in the same fashion as the type of the type die. The type embossments of the type wheels are designated throughout by the numeral 28. Rotatably mounted on the pawl frame members 21 is a controlling cam shaft 29 carrying a plurality of cams, designated respectively 30, 31, 32 and 33. The contour of these several cams is identical, but they are arranged at different circumferential positions on the cam shaft so that their dwells are separated by an angular distance of 90°, and the dwells of no two are on the same side of the shaft. A stub pin 34 is fixed coaxially to the cam shaft, and extends through an arcuate slot 35 in the right hand side cover plate, exterior of which it carries a knurled head 36, by manipulation of which the cam shaft may be rotated. As best seen in Figs. 4 and 8, the pin 34 carries a detent cam 37 having four peripheral seats 38 arranged at angular distances of 90°. A detent 39 mounted on the outer side of the right hand pawl frame member 21 is pressed into engagement with the pe-

periphery of detent cam 37 by a spring 40, and its nose is adapted to register in the seats 38. In such position the detent is effective to restrain the cam shaft against 5 rotation, but the application of sufficient torsion to the head 36 is effective to cam the detent out of a seat 38 and effect rotation of the cam shaft. A transversely extending rod 41 is mounted in pawl frames 21 and forms a mounting for pawls 42, 44, 45 and 46, which pawls are independently rotatable on said rod. The form of these pawls is best illustrated in Fig. 7, and the respective pawls contact the peripheries of 15 the respective cams 30, 31, 32 and 33, and their noses are adapted for cooperation with the respective ratchet wheels 24', 25', 26' and 27'. The relationship of these members is such that when a pawl lies in the dwell of 20 its controlling cam, its nose will lie in front of a tooth of its associated ratchet wheel. The pawls are restrained in contact with the controlling cams by leaf springs 47 which are mounted on the transverse frame 25 member 22. By virtue of the spacing of the dwells of the controlling cams about the cam shaft, only one of the pawls at a time may lie in position to engage a ratchet wheel, the other pawls being held in lifted 30 position by the high portions of their controlling cams. Oscillation of the pawl frame forwardly may be accomplished by forward pressure upon the head 36, and will cause the pawl in lowered position to engage a tooth 35 of its associated ratchet wheel and rotate such ratchet wheel and its conjoined type wheel to a degree determined by the extent of the slot 35. The degree of movement permitted by the slot is that necessary to move 40 a type embossment 28 to printing position in the slot of the die plate. Proper register of the type of the type wheels is attained by detents 48 pressed by stiff springs 49 into engagement with the ratchet wheels, and formed with inclined faces adapted to fit between the ratchet teeth and center the type, there being such a detent and spring provided for each ratchet wheel, and the same being mounted upon lugs 19 of the casing. The return or rearward movement of the pawl frame is induced by a spring 50 mounted at one end on the housing, which movement carries the pawl in effective position back to a position behind the next tooth of the ratchet wheel. As the pawl frame 55 swings rearwardly under influence of its spring 50, the effective pawl rides on the inclined face of the ratchet tooth, and tends to take up any overthrow of the wheel and secure alignment by pressing the tooth face against the nose of the detent 48. The pawls 34 may be rendered effective selectively to operate their type wheels in this fashion by adjustment of the control cam shaft 29 as 60 above described, proper indicia being in- scribed on the head 36 to determine the adjustment. These are shown in Fig. 2 by the legends "Year," "Month," "1 Day" and "2 Day," referring respectively to the year type wheel, month type wheel and first and second day type wheels.

Ribbon feed.

As a means for marking the impression of the type upon paper or the like, an inked ribbon is provided, with suitable mechanism for feeding it progressively upon operation of the stamp. The ribbon is indicated by the numeral 51, and it is wound upon the ribbon shafts 52 and 52', which shafts are 75 journaled in the side cover plates 15 and carry respectively spur gears 53 and 53' and knurled heads 54 and 54' on the exterior of the left hand side cover plate. The ribbon passes downwardly through slots in the housing, and around over the printing surface of the type die plate 16 and the type bosses of the type wheels which are presented in printing position. The means for 80 rotating the ribbon shafts to feed the ribbon includes as a prime mover the link 55 which is pivoted at 56 on the base frame in front of the pivot of the swinging frame, and extends through a slot in the housing to a pivotal connection 57 upon a swinging 85 arm 58 which is pivoted upon the shaft 20. As the swinging frame 2 is moved downwardly, this link 55 is moved inwardly and the plate 58 swung forwardly. The plate 58 carries a spring pressed ribbon feed 90 pawl 59 which has operative engagement with a ratchet wheel 60 rotatably mounted on a shaft 61 which is journaled on an arm 62 pivotally mounted on shaft 20. Conjoined to the ratchet wheel 60 for rotation therewith is a spur gear 64 which is adapted to mesh selectively with spur gears 53 and 53' of the ribbon shafts, depending upon the angular position of the plate 62 on shaft 100 20. Movement of the pinion 64 into engagement with pinions 53 and 53' is effected by means of a shiftable head 65 which is movable longitudinally on a pin 66 fixed concentrically to gear 64 and ratchet wheel 60 and operating through an arcuate slot 67 in the left hand side cover plate. The end portions of this slot are enlarged to receive a latch hub 68 of the head 65, and said head is restrained inwardly on the pin 66 by 105 means of a spring 69 which tends to move the hub into such relation. To shift the gear 64, therefore, the head 65 is pulled outwardly to disengage the hub 68 from the slot enlargement, and the head pressed forwardly or rearwardly, as the case may be, to swing the pin 66 through the narrower portions of the slot to a position where the hub may register in the other end enlargement. This will move the pinion 64 from 110 mesh with one of the pinions 53 or 53' into 115 mesh with the other. The head 65 is restrained 120 rearwardly by a spring 70 which tends to move the head 65 forwardly. The head 65 is 125 restrained forwardly by a spring 71 which tends to move the head 65 rearwardly. The head 65 is 130 restrained rearwardly by a spring 72 which tends to move the head 65 forwardly.

mesh with the other thereof, the feed pawl 57 remaining in engagement with the ratchet wheel 60. Incident to the movement of the link 55, with the pinion 64 in either position, the feed ratchet 59 will be moved forwardly over the ratchet wheel 60, and upon upward movement of the swinging frame, the retraction of link 55 will cause ratchet wheel 60 to be rotated rearwardly a limited distance. The rotation of pinion 64 effected thereby will operate to feed the ribbon in one direction when said pinion is in engagement with the pinion 53, and in the opposite direction when it is 10 in engagement with the pinion 53'. The ribbon may be fed independently of the operation of the stamp by rotation of either ribbon shaft by means of this knurled head 54 or 54'. Rearward rotation of the ratchet wheel 60 is prevented by a detent 70 carried 20 on the plate 62.

As a means for indicating the location of the ribbon as between the two ribbon shafts, a telltale device is provided, the same constituting a stub shaft 71 mounted in the right hand side cover plate and carrying at its outer end a pointer 72 and at its inner end a lever 74 adapted to rest upon the ribbon wound on the front ribbon shaft, under the pressure of a spring 75. Indicating graduations are provided on the side cover plate in association with the pointer 72, from which the approximate proportion of the ribbon wound on the forward ribbon shaft 30 may be determined, so that the reversal of feed by adjustment of the pinion 64 as above described may be made at proper times.

As a means for determining by convenient inspection what type characters of the type wheels are in printing position, the wheels are provided with indicators 76, preferably 40 printed on white celluloid or the like, and mounted between the type bosses at such angular relationship to the several type characters as to be readable through an inspection opening 77 in the front of the housing when corresponding characters are presented 45 at the printing position.

It is believed that the operation of the 50 several parts of the device has been made clear in the foregoing, so I will here describe simply certain operations in their general or cooperating relationship. In the setting up of a date, the control cam shaft 29 is rotated to proper position, as may be observed from the legends on the head 36, to engage a selected type wheel, for example, the month type wheel. The pawl frame 21 is then swung forwardly by pressure on the head 36, advancing the month type wheel one step. This is repeated until the proper month type boss is presented at the printing position. The control cam shaft is then shifted to engage, say, the first day wheel, 60 and the pawl frame oscillated as many times

as may be necessary to move the proper type boss to position. Similar shifting of the control cam shaft and oscillation of the pawl frame is effected to properly position the second day wheel and the year wheel. 70 The sheet upon which the printing impression is to be made is then laid upon the platen, with the portion to receive the printing impression up. The operator may thus accurately position the sheet which he desires to stamp, so that the printing may be effected at the place desired. The swinging frame 2 is then swung down to make impact upon the sheet on the platen, and the printing is effected through the ribbon by 75 the type of the printing die plate and of the type bosses in printing position. Incident to the downward movement of the swinging frame, the ribbon feed link 55 is shifted inwardly, thus rotating the swinging plate 58 80 and carrying the feed pawl 59 forwardly over the ratchet wheel 60. Upon the release of the swinging frame, it is raised by the influence of spring 8, incident to which movement the rearward shifting of link 55 rotates pinion 64 by virtue of the engagement of feed pawl 59 with ratchet wheel 60. This movement is transmitted through either pinion 53 or 53' with which pinion 64 is in mesh, and the ribbon is fed by the 90 consequent rotation of the actuated ribbon shaft. When the direction of feed is to be reversed, the pinion 64 is shifted into engagement with the other ribbon shaft pinion, in which position it is retained by the 95 engagement of hub 68 in the end enlargement of the slot 67. In setting the stamp for a following day in the same month, only 100 a single oscillation of the pawl frame is necessary, excepting when changing from 9 to 10 or from 29 to 30.

A stamp embodying features as above described possesses very distinct advantages. The disposal of the printing members and ribbon on the movable frame or head portion of the stamp makes the printed impression right side up where it may be inspected by the operator while the printed sheet is still on the platen. This feature 110 also permits the operator to position the sheet accurately on the platen so that the impression may be stamped exactly where he desires it. The fashion of mounting and operating the type wheels provides a very compact structure which does not render the head of the machine unduly large, and at the same time secures accurate aligning 115 and security against over-throw incident to violent operation of the device. The rotation of the type wheels in the manner described permits the utilization of a very heavy detent spring for holding and aligning the type, as the leverage between the head 36 and the shaft 20 is sufficiently long 120 to render the intentional operation of the 125 sheet on the platen difficult. The 130

wheels quite easy. The mechanism is easily assembled, and the printing type die may be removed and replaced independently of other parts. Pressures received by the type wheels incident to making an impression are transmitted to the substantial type wheel shaft 20, which by virtue of the fact that it may be a solid shaft, is particularly adapted to sustain them, all of the setting and retaining mechanism for the type wheels being entirely relieved from these pressures. The ribbon feeding mechanism is compact and simple, and is operated incident to the use of the stamp, for feeding the ribbon in either direction.

I claim:

1. In a dating stamp and the like, the combination of a fixed platen, a plurality of type wheels movable relative to the platen for printing operations, setting means carried with the type wheels and movable relative thereto to effect adjustment thereof, and means for controlling the effectiveness of said setting means on the respective type wheels.

2. In a device of the class described, the combination of a plurality of coaxially mounted type wheels, a plurality of pawls arranged for oscillatory movement on an axis concentric with the wheels, means whereby said pawls may be swung, and means for determining the effectiveness of the pawls selectively upon the type wheels to move the same upon movement of said pawls.

3. In a device of the class described, the combination of a plurality of concentrically mounted type wheels and a cooperating platen disposed for compressive cooperation, means for detaining the type wheels selectively in different rotative positions, setting means effective upon peripheral portions of the wheels to accomplish rotation thereof, and means for controlling the effectiveness of said setting means upon the wheels selectively.

4. In a device of the class described, the combination of a platen and a type wheel mounting arranged for relative movement, a plurality of type wheels movable severally on said mounting, and setting means pivoted on the mounting concentrically with the wheels and effective upon peripheral portions of the wheels selectively to vary their rotative positions thereon.

5. In a device of the class described, the combination of a supporting frame, a movable frame member supported thereon, adjustable printing members carried on said movable frame, a platen supported on the supporting frame member, a ribbon supported on the movable frame member in cooperation with said printing members, and ribbon feeding mechanism carried on the movable frame member and operable inci-

dent to movement thereof to feed the ribbon in either of opposite directions.

6. In a device of the class described, the combination of a supporting frame member, a movable frame member supported thereon, 70 a platen on the supporting frame member, shafts for reeling a ribbon supported on the movable frame member, a rotating device mounted on the movable frame member and operated incident to movement thereof, and 75 means for retaining said rotating device in operative connection with said ribbon shafts selectively.

7. In a device of the class described, relatively movable frame members, a platen supported on one thereof, a wheel mounting fixed on the other thereof, severally operable type wheels adjustably supported on said mounting for impact with said platen, an oscillatory frame supported in association with said wheels, pawls on said frame for engagement with said wheels, means for rocking said frame, and means for controlling the effectiveness of said pawls upon 80 said wheels.

8. In a hand stamp, the combination of a platen and a type wheel mounting arranged for relative movement, a plurality of type wheels mounted on the mounting and adjustable severally to position type thereon 85 relative to the platen, detents effective upon the wheels to maintain type thereon in alignment at the printing position, and means operable upon the wheels to adjust them on the mounting, said means being effective in one direction to move the wheels past the detents and in the opposite direction to move the wheels against the detents to align the type.

9. In a hand stamp the combination with a platen and a wheel mounting arranged for relative movement, of a plurality of type wheels severally adjustable on the mounting, a pair of arms disposed one on each side of the wheels and rotatable relative thereto on a common axis, a plurality of pawls supported by said arms, means for controlling engagement of said pawls with said wheels, and means operable to rock the arms to rotate the wheels.

10. In a hand stamp, the combination with a platen and wheel mounting arranged for relative movement, of a plurality of type wheels adjustable on said mounting, each of said wheels being provided with a conjoined ratchet wheel, manually operable means movable relative to the wheels, pawls carried by said means for engagement with the ratchet wheels, and means for controlling position of said pawls to render them effective and ineffective upon the ratchet wheels.

11. In a device of the class described, the combination of a platen and a wheel mounting arranged for relative movement, a plu-

105

110

115

120

125

130

rality of type wheels adjustable severally on the mounting, each type wheel having a conjoined ratchet wheel, a swinging frame associated with said wheels, pawls on said swinging frame arranged for engagement with the ratchet wheels to rotate the type wheels, and a plurality of conjointly operated position determining elements effective to determine the effectiveness of the 10 pawls upon the ratchet wheels.

12. In a device of the class described, the combination with a platen and a wheel mounting arranged for relative movement, of a plurality of type wheels severally adjustable on the mounting, each of said type wheels having a conjoined ratchet wheel, a swinging frame associated with said wheels, pawls carried by said frame for engagement with the ratchet wheels, and adjustable elements 20 dissimilarly effective upon the pawls severally to control their effectiveness upon the ratchet wheels.

13. In a dating stamp and the like, the combination of a stationary frame, a swinging frame, a platen supported on the former, a series of adjustable type wheels supported on the swinging frame for cooperation with the platen, a printing ribbon supported on the swinging frame for cooperation 30 with the type wheels and platen, a swinging arm pivoted on the swinging frame, pawls supported for movement by said arm, means for positioning said pawls to render them effective and ineffective upon 35 the type wheels selectively, and means whereby the swinging arm may be moved to render the pawls effective to adjust the wheels.

14. In a stamping device, in combination, 40 a supporting frame, a swinging frame movably mounted thereon, type carried on the swinging frame, ribbon reels carried on the swinging frame in association with the type, a ribbon extending across the type and connected with the reels, a gear carried on the 45 swinging frame and adjustable into opera-

tive engagement with either reel, a pawl for driving the gear, and a lever connected to the supporting frame and controlling the pawl to effect actuation of the gear upon 50 movement of the swinging frame.

15. In a stamping device, in combination, a supporting frame, a swinging frame mounted thereon, type carried on the swinging frame, ribbon reels carried on the 55 swinging frame at opposite sides of the type, a ribbon connected to the reels and extending across the type, an arm pivotally mounted on the swinging frame, a gear rotatably mounted on said arm, means for adjusting said gear into operative engagement with either of the reels, a pawl co-operating with the gear, and a lever secured to the supporting frame for controlling position of the pawl whereby the gear and the 60 reel engaged thereby may be rotated upon 65 movement of the swinging frame.

16. In a stamp, in combination, a supporting frame, a swinging frame mounted 70 thereon, type wheels mounted on the swinging frame, ribbon reels mounted on the swinging frame at opposite sides of the type wheels, a ribbon connected to the reels and extending across the type wheels, an arm pivoted concentrically with the type wheels, 75 a gear carried on said arm and adapted for operative engagement with either reel, means for retaining said arm in selected position on the swinging frame, a lever connected to the supporting frame, a pawl controlled by said lever and operably engaging the gear, whereby the gear may be fed upon movement of the swinging frame relative to the pawl.

In testimony whereof I have hereunto 80 subscribed my name in the presence of two 85 subscribing witnesses.

MORRIS SHERAS.
